UNITED STATES PATENT OFFICE.

CHARLES F. MASSEY, OF CHICAGO, ILLINOIS.

BATTERY-WELL.

951,192.

Specification of Letters Patent. Patented Mar. 8, 1910.

Application filed February 6, 1909. Serial No. 476,406.

To all whom it may concern:

Be it known that I, CHARLES F. MASSEY, a citizen of the United States, residing at Chicago, in the county of Cook and State of Illinois, have invented certain new and useful Improvements in Battery-Wells, of which the following is a specification.

The present invention relates to certain features of improvement on the battery well described and claimed in the Massey patent, No. 891,944, issued June 30, 1908. Battery wells of this character are intended more particularly for the storage of batteries which are required in the operation of railroad block signal appliances and track circuits, or in the operation of electrical apparatus of any style or character in which it is necessary to provide reservoirs for the storage of batteries at points distant from houses or buildings in which the batteries might otherwise be located.

Battery wells for railroad purposes are ordinarily buried beneath the surface of the ground, in order to protect the batteries contained within the well from freezing; and it is obvious that in these conditions it will be necessary to frequently locate the wells at points where the ground conditions are unfavorable for their reception, which is particularly the case where the ground is soft or marshy, and where there is a consequent tendency for the well to be lifted more or less out of the ground, by reason of its natural buoyancy.

The object of the present invention is to so construct and arrange the well that the body of the well can be buried below the frost line and to an extent necessary to counteract the buoyancy of the well by the weight of the earth above it, and at the same time afford means for ingress into the interior of the well through a neck arranged to project above the surface of the earth.

Other objects of the invention are, to provide a suitable socket for the reception of the trunking box, and also to provide a suitable conduit pipe for the battery wires, and convenient means for their suspension within the interior of the well.

Further objects will appear from a detailed description of the invention, which consists in the features of construction and combination of parts hereinafter described and claimed.

In the drawings, Figure 1 is a perspective sectional elevation, showing the interior of

the battery well of the present invention; and Fig. 2 a side elevation, taken at right angles to the section line of Fig. 1.

The well is preferably formed of reinforced concrete, comprising a cylindrical lower wall 3 which springs from a flat floor 4. The cylindrical lower wall 3 merges into a converging upper wall 5, which connects with a flat roof 6 which is cut away, in its center, to provide a circular opening 7 adapted to be closed by means of an inner cover 8, which rests upon a ledge or flange 9 constituting the inner edge or rim of the roof 6. The circular opening 7 communicates with the interior of an upper air chamber 10, having a cylindrical wall 11 which extends upwardly a distance preferably equal to about half the diameter of the lower portion of the battery well and gives the upper portion of the well a neck-like formation. The inner diameter of the cylindrical wall 11 is such that the ledge or flange 9 will project inwardly therefrom to a degree necessary to afford a support for the inner cover 8. The top of the air chamber is closed by means of a flanged outer cover 12 which fits over the edge of the air chamber wall, and is adapted to be held in place by means of chain sections 13 connected in their center by a padlock 14 or other suitable locking means. The outer ends of the chain sections are carried down over the edges of the cover and are connected to eyes 15 entered in the wall 8 of the air chamber. Obviously, other means of securing the cover in place might be employed.

The well is provided, on one side of the air chamber wall, with a thickened lug 16 which extends upwardly from the roof 6 to a point near the upper edge of the wall 10, which flange has entered therethrough a conduit pipe 17 of elbow shape, which pipe is preferably formed of fiber or other similar anti-corroding substance, and serves to convey the wires from the batteries within the well to a square trunking box 18, the inner end of which is entered within a square socket recess 19 with which the upper end of the conduit pipe communicates.

As previously stated, the well is preferably formed of reinforced concrete, the walls being formed upon a framework or skeleton 20, which may be in the form shown in Patent, No. 891,944, or of other suitable formation. The present invention is not concerned with the formation of the framework,

so that it is not deemed necessary to enter into a description thereof. As shown, however, in Fig. 1, the framework comprises a plurality of rods embedded in the concrete, 5 and, in order to afford suitable hangers for the suspension of the battery wires under the roof of the battery chamber, the rods comprising the framework or skeleton are provided with loops or eyes 21, which project through the inner surface or ceiling of the horizontal roof 6 and afford supports for the wires, so that the latter may be laid under the ceiling to the conduit pipe, thereby leaving the center of the battery chamber 10 unobstructed by wires, so that the attendant can descend into the battery chamber through the opening 7 without danger of entanglement with the wires. It will be understood that the batteries are supported 15 on tiers 22 which are arranged around the circular walls of the battery chamber.

The battery wells, when in use, are buried in the ground to the degree necessary to bring the battery chamber below the frost 20 line, for which purpose the elongated neck portion of the structure is provided. When buried in this manner, the upper end of the neck will project slightly above the surface of the ground and afford a suitable means 25 for access to the interior of the well. The reduced diameter of the neck, as compared with the lower portion of the well, affords a flat roof connecting with sloping side walls, so that, when the well is buried to the 30 desired degree, a very considerable weight of earth, will rest directly upon the top of the lower or enlarged portion of the battery well, which mass of earth serves to counteract the tendency of the well to be lifted to a 35 greater or less degree above the surface of the ground, by reason of the buoyancy of the well. Unless the well be buried to a very considerable degree, this natural buoyancy, especially in moist or marshy ground, or in 40 time of flood or heavy rains, would lift the well to such an extent as to raise it or a portion of it above the frost line, with the result that the batteries might be frozen during subsequent cold weather.

45 The formation of the well of the present invention is such that this buoyant tendency is overcome, and at the same time a suitable air chamber and means of access are provided. The formation of the conduit pipe 50 and the manner in which it is embedded, and the formation of the trunking box socket, afford sufficient rigidity to prevent displacement of the trunking box, even in

the event that the battery well should be lifted more or less by its buoyancy under unfavorable weather conditions. By providing a deep socket for the inner end of the trunking box, the latter will rise and fall with the well without breaking off or materially displacing the wires, which would be 55 the case if there were any relative movement between the trunking box and the well. The arrangement, furthermore, is one which affords a relatively large battery chamber and a relatively small air chamber and neck, so that the capacity of the well, as compared with its weight and total size, will be large. 60

The sloping upper side walls, in addition to the aid they afford in sustaining the mass of earth above the well, impart to the upper portion of the battery chamber a rigidity and strength of construction which enable the flat roof to sustain the superimposed load of earth without increasing the thickness or weight of the structure at this point. 65 The construction, as a whole, is strong, neat and durable, and well adapted to meet all the conditions encountered in actual use. 70

What I regard as new and desire to secure by Letters Patent is:

85 1. A battery well, having a battery chamber, and having above the battery chamber a thickened lug formed in the wall of the well having therein a conduit passage terminating in a socket recess adapted to receive the end of a trunking box, substantially as described.

90 2. A battery well, having a battery chamber and having above the chamber a thickened lug formed in the wall of the well, a conduit pipe of elbow shape and formed of non-corrosive material, as fiber, the lug having formed, in register with the end of the pipe, a socket recess adapted to receive the inner end of a trunking box, substantially as 95 described.

95 3. A battery well, having a battery chamber, and having above the battery chamber an air chamber which communicates with the battery chamber through a manhole, said air chamber having in its vertical side wall an upwardly extending conduit passage which at its lower end opens directly into the battery chamber and at its upper end leads to the exterior of the well at a point intermediate the height of the air chamber. 105 110

CHARLES F. MASSEY.
